A. H. JEWELL

DEPENDING SHIELD ATTACHMENT FOR OIL STOVES

Filed March 29, 1923

UNITED STATES PATENT OFFICE.

ALBERT H. JEWELL, OF LAWRENCE, KANSAS, ASSIGNOR TO THE PERFECTED CHIMNEY COMPANY, OF LAWRENCE, KANSAS, A CORPORATION OF KANSAS.

DEPENDING SHIELD ATTACHMENT FOR OIL STOVES.

Application filed March 29, 1923. Serial No. 628,475.

To all whom it may concern:

Be it known that I, ALBERT H. JEWELL, a citizen of the United States, residing at Lawrence, in the county of Douglas and 5 State of Kansas, have invented a certain new and useful Improvement in Depending Shield Attachments for Oil Stoves, of which the following is a specification.

My invention is designed as an attachment to be placed on any of the standard, or usual, oil stoves in common use and has 10 for its object to prevent loss of heat by radiation in conducting the heat from the burner up through the chimney and to the utensil which sits on the spider on the 15 stove. It directs the heat from the chimney to the cooking utensil, thereby securing the greatest results from the heat produced.

A further object is to produce such a device in an inexpensive construction that may 20 be applied in a simple and easy manner to any oil stove now in use.

My invention consists of certain details 25 of construction hereinafter set forth, pointed out in my claims and illustrated in the accompanying drawings, in which Fig. 1 shows a plan view of part of an oil stove to which my device has been attached;

Fig. 2 shows a sectional view taken on the 30 line A—A of Fig. 1; and

Fig. 3 shows a detail view illustrating my means of ventilating my device.

Referring to the accompanying drawings the reference numeral 10 is used to indicate 35 the top of an oil stove with an opening therein to receive the spider 11, said opening, preferably, being provided with a depending flange 12, surrounding the same.

My device is principally comprised of 40 two mating cone shaped parts 13 and 14, the two forming in their combination a continuous inverted cone, or shield, the upper open end being designed to underlie the spider on the stove and the lower open end, 45 in normal position, being designed to be immediately above the open end of the stove chimney 15, these two openings being of substantially the same size. The lower part 14, of the inverted cone, projects into the 50 lower end of the upper part 13, as shown, the opening at the top of the lower part being larger than the opening at the lower end of the upper part. These parts are not fastened together, except in this practically 55 telescoping manner, thus providing for the

lower part easily moving upwardly, under pressure, into the upper part when it is desirable to change a stove chimney.

The upper part is also provided with a plurality of lugs 16, by means of which it is suspended from the stove top, the usual manner of joining my device to the stove being to remove the spider and lower the shield through the opening, the lugs engaging the stove top and providing suspension 60 means. In some cases the whole stove top is comprised of a spider and in such constructions the shield may be suspended from the spider work.

In order to provide for cases where the 70 cooking utensil might overhang the spider and thereby close off the space between the spider ribs and consequently close the space for the removal of the products of combustion, I have provided a sliding damper for 75 the upper member of my shield. I accomplish the purpose of providing ventilation in such cases, by placing a plurality of orifices, 17 through the wall of the upper member, and mounting, for slidable movement, 80 on the inner surface of the member, and designed to close the orifices 17, a damper 18. A corresponding number of similar orifices 19 are provided in the damper and are designed to be in proper alinement with the 85 orifices 17, and of the same size. When the damper has been moved to bring the orifices 19 into register with the orifices 17 it provides free passage through these orifices for the products of combustion. The 90 orifices 17 may be entirely freed by perfect registration with the orifices 19, or the damper can be moved so that it overlaps any desired portion of the orifices 17, thereby selectively regulating the amount of ventilation.

Having thus described my invention what I claim and desire to secure by Letters Patent of the United States, is:

1. An attachment for an oil stove comprising a depending shield composed of two mating cone-shaped members, one movable within the other, with means for suspending the shield beneath the spider of the stove, its lower extremity being positioned 100 above the opening of the stove chimney.

2. An attachment for an oil stove comprising a depending shield composed of two mating cone-shaped members, one movable within the other, with means for suspend- 105

ing the shield beneath the spider of the stove, its lower extremity being positioned above the opening of the stove chimney said members being provided with orifices, the 5 orifices in one member being in lineal alignment with the orifices in the other member, and the inner member being in slidable engagement with the outer member.

3. An attachment for an oil-stove comprising a depending shield composed of two 10 mating cone-shaped members, one movable

within the other, with means for suspending the shield beneath the spider of the stove, its lower extremity being positioned above the opening of the stove chimney one member being provided with a plurality of orifices, and a damper, provided with orifices in alignment with the orifices in the said member, being attached for slidable movement in said member.

15

ALBERT H. JEWELL.
